US00D823302S

(12) **United States Design Patent** (10) **Patent No.:** **US D823,302 S**
(45) **Date of Patent:** **** Jul. 17, 2018**

(54) **PORTABLE WRIST WEARABLE DEVICE**

(71) Applicant: **LG ELECTRONICS INC.**, Seoul (KR)

(72) Inventors: **Max Yoshimoto**, Sunnyvale, CA (US); **Christophe Koch**, Santa Cruz, CA (US); **Alberto Villarreal**, San Jose, CA (US); **Hyenseung Seo**, Seoul (KR); **Seongjae Lim**, Seoul (KR); **Seala Park**, Seoul (KR)

(73) Assignee: **LG ELECTRONICS INC.**, Seoul (KR)

(**) Term: **15 Years**

(21) Appl. No.: **29/593,241**

(22) Filed: **Feb. 7, 2017**

(51) LOC (11) Cl. **14-02**

(52) U.S. Cl.

USPC **D14/344**; D10/32

(58) **Field of Classification Search**

USPC ... D10/30-32, 38, 40, 41, 46, 70, 79, 106.5, D10/106.6, 106.92, 106.94, 114.6, 123, D10/125, 126, 128, 131; D11/1-4, 93, D11/94; D14/138, 144, 641, 644, 658, D14/485; D24/167, 169, 186, 187

(57) **CLAIM**

The ornamental design for a portable wrist wearable device, as shown and described.

DESCRIPTION

FIG. 1 is a perspective view of a portable wrist wearable device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the portable wrist wearable device that form no part of the claimed design.

1 Claim, 7 Drawing Sheets
